UNITED STATES PATENT OFFICE.

GUSTAV C. KALIES, OF BUTTE, MONTANA.

DIRECTION SIGNAL.

Application filed May 18, 1927. Serial No. 192,413.

This invention relates to new and useful improvements in signaling devices, and particularly to devices used on automobiles for signaling a change of direction.

5 One object of the invention is to provide a novel and simple device which is easily operable by the driver of the automobile, to display a signal, to be seen by the drivers of other automobiles, by means of which they 10 will be apprised of an intended change of direction.

Another object is to provide a device of this character which includes a small statue having arms which are adapted to be elevated, 15 successively, in a novel manner.

Another object is to provide a device of this character wherein the statue contains a source of light which is adapted to be projected into the elevated arm, such arm being 20 semi-transparent, so that it will appear illuminated, to be readily seen by others.

Other objects and advantages will be apparent from the following description when taken in connection with the accompanying 25 drawing.

In the drawing:

Figure 1 is a front elevation of the statue, with the air controlling valve and connecting pipes in diagrammatic form, the figure having one arm raised.

Figure 2 is an enlarged vertical sectional detail view through the statue.

Figure 3 is an enlarged vertical sectional view through the air controlling valve.

35 Figure 4 is a plan view of the top plate of the valve.

Figure 5 is a plan view of the valve plate.

Figure 6 is an enlarged vertical sectional detail view of the shoulder portion of the 40 figure, showing the construction of the attached portion of the arm.

Referring particularly to the accompanying drawing, 10 represents a statue of a man, which is fixed on the hinged radiator cap 11, 45 and faces toward the front, or in the direction in which the automobile is traveling. The statue is preferably formed from colored glass or china, and has openings 12, at the shoulders thereof. Secured in covering relation to each of the openings 12 is a thin rubber bag, in the form an arm and hand, such arm being normally collapsed, and hanging at the side of the figure. Disposed within the figure, or statue, is an electric 50 lamp 14, receiving current from any suitable source, by means of the wires 15. That por-

tion of the arm which is attached in the opening 12 is closed, except for a small opening 16, in the lower side thereof, in which is secured an end of a small rubber hose 17, 60 said hose leading down through a channel 10', in the side of the figure, and out of the base thereof, where it is connected, by means of a coupling 18, with a pipe 19, leading to the controlling valve 20, which will be 65 more specifically described later herein. It will be noted that there is a hose 17 connected with each arm 13. Secured within an opening 13', in the inner end of the arm 13, is a glass disk 21, which transmits the 70 light from the interior of the figure, to the interior of the arm, when such arm is inflated, and in elevated position.

The air controlling valve comprises an upper plate or disk 22, a lower plate or disk 23, of the same diameter as the upper disk, and the intermediate valve disk 24 having the outwardly extending handle 25. Disposed on the upper disk 22, and having its flange 26 secured to said disk, by means of 80 the screws 27, is a compressible rubber bulb 28, which is adapted to be squeezed by the hand of the driver of the automobile, such bulb being located within easy reach of the driver. In the upper and lower disks 22 and 85 23 are formed the pairs of registering openings 29 and 30, while in the valve disk are formed two openings 31 and 32, these latter openings being spaced a shorter distance apart than either of the first mentioned 90 pairs. The disks are connected together by the vertical bolts 33, and formed in the periphery of the valve disk 24 are recesses through which said bolts pass, whereby to permit proper pivotal movement of the valve 95 disk. When the valve disk is swung in one direction its opening 31 will register with the openings 29 and when swung in the opposite direction its opening 32 will register with the openings 30. By reason of the fact 100 that the openings 31 and 32 are closer together than the openings 29 and 30, it is impossible to register both of these openings 31 and 32 with the openings 29 and 30, whereby air will flow through only one 105 opening. Connected to the lower ends of the openings 29 and 30, of the lower disk 23, are the nipples 33, and connected to said nipples, by means of the couplings 34, are the other ends of the before-mentioned pipes 19. A bolt 35 is disposed vertically through the centers of the disks to permit proper 110

tation of the valve disk between the upper and lower disks.

Upon swinging the valve disk in one direction, and then squeezing the rubber bulb 28, the air contained in said bulb will be forced through the openings 29, of the upper and lower disks 22 and 23, and the opening 31, of the valve disk 24, and out through one of the pipes 19, to enter one of the arms 10 of the statue, whereby to inflate the said arm. Upon the arm being inflated, said arm will rise into horizontal outwardly extended position, so as to point in the direction in which the driver intends to go. The rubber, from which the arm is formed, being thin, will be semi-transparent, or translucent, so that the light from within the figure will shine through the lens, and illuminate the interior of the arm, so that the arm will be readily seen by other drivers. Upon turning the valve disk in the opposite direction, the other openings of such disk will register with the openings 30, and permit air to pass through the other pipe 19, upon the 25 bulb being compressed. If desired, the driver can hold the arm in elevated position by swinging the valve disk, after having inflated the arm, so that the openings of said disk are both out of register with the 30 openings of the disks 22 and 23. Then, upon swinging the valve disk in either direction, the air will be permitted to flow back into the rubber bulb.

While I have illustrated and described 35 the statue of the man mounted on the ra-

diator cap, I wish it understood that I also intend to mount a similar figure at the top of the automobile, suitable connections being made to the second figure, by tapping in on the pipe 19.

40

What is claimed is:

1. A direction signal including a hollow figure having armholes formed with surrounding ledges, an arm formed of inflatable material having one end disposed in an arm-hole and formed with centrally apertured end wall and a circumscribing flange, a packing ring secured on said ledge and having said flange secured thereto, an air conduit extending upwardly through the body 50 and connected to the arm within the body, and a transparent disk within said aperture of the wall.

45

2. A direction signal including a hollow translucent body having an opening in one side provided with a ledge, a hollow inflatable translucent arm having an end closing wall provided with a central aperture, a flat ring secured on said ledge, the said flange being secured to the said ring, an air 60 conduit in a wall of the body connected with said inflatable arm, a centrally apertured disk secured to the other side of said wall and flange, a source of light within the body, and a lens secured within the aperture of 65 said disk.

55

In testimony whereof, I affix my signature.

GUSTAV C. KALIES.
